CLAIM

The ornamental design for an outdoor lighting fixture, as shown and described.

DESCRIPTION

FIG. 1 is a front perspective view of an outdoor lighting fixture showing our design according to a second embodiment;

FIG. 2 is a rear perspective view thereof, opposite the view of FIG. 1;

FIG. 3 is a top plan view thereof;

FIG. 4 is a bottom plan thereof, opposite the view of FIG. 3;

FIG. 5 is a first side view thereof;

FIG. 6 is a second side view thereof, opposite the view of FIG. 5; and,

FIG. 7 is a third side view thereof, the opposing side being a mirror image of that shown.

The dashed broken lines are included for the purpose of illustrating environment of the design and form no part of the claimed design. The dot-dash broken lines represent boundaries of the claimed design. None of the broken lines form part of the claimed design.
